UNITED STATES PATENT OFFICE

146,724

DESIGN FOR A SHOE SOLE

John E. Ryan, Danbury, Conn.

Application May 1, 1946, Serial No. 129,180

Term of patent 14 years

(Cl. D7—5)

To all whom it may concern:

Be it known that I, John E. Ryan, a citizen of the United States, residing at Danbury, in the county of Fairfield and State of Connecticut, have invented a new, original, and ornamental Design for Shoe Sole, of which the following is a specification, reference being had to the accompanying drawing, forming part thereof.

Figure 1 is a plan view of the tread surface of a shoe sole, showing my new design; and

Figure 2 is a side elevational view thereof.

I claim:

The ornamental design for a shoe sole, as shown.

JOHN E. RYAN.
